George Elmer Eastham
J.W. Haslett, Atty.

UNITED STATES PATENT OFFICE.

GEORGE ELMER EASTHAM, OF EVANSVILLE, INDIANA.

THREADING DIE.

Application filed January 18, 1927. Serial No. 161,809.

This invention relates to threading dies.

The object of my invention is to provide an improved threading die which can be opened out to permit sharpening of the cutters thereof by a high speed emery wheel, thus enabling the die to be used for an indefinite period, if repeatedly re-sharpened.

A convenient construction, embodying the invention, comprises a two-part die whose parts or sections are hinged together, enabling the sections to be opened out when re-sharpening of the cutters becomes necessary, and means for locking the sections together for use. One such locking means is that hereinafter described, namely, a ring-like holder or chuck which is adapted to encircle the die-sections when they are closed.

In the accompanying drawings:

20 Fig. 1, is a face view of the die when closed;

Fig. 2, is a similar view, showing the die locked in its chuck;

Fig. 3, is an edge view of the die, showing the hinge;

Fig. 4, is a face view of the die, opened out;

Fig. 5, is a view like Fig. 1, showing a modification;

30 Fig. 6, is a face view of the die of Fig. 5, opened out;

Fig. 7, is an edge view of the die of Fig. 5, showing the hinge thereof; and

35 Fig. 8, is a view showing the die of Fig. 5, opened out and being ground or re-sharpened by a high-speed emery wheel.

Referring first to Figs. 1 to 4 inclusive, instead of the die being in a single, solid piece, it is in sections 1 and 2 hinged together in 40 any suitable manner at 3, one of the sections having a cut-away part 4 to permit full opening of the two sections as shown in Fig. 4.

The free ends of the sections have flat mat- 45 ing faces indicated at 5.

The chuck for holding the sections 1 and 2 locked tightly together in closed position, appears at 6 and is provided with a set screw 7 for clamping the die against rotation in said ring or chuck 6. The entire die and ring or chuck, as shown in Fig. 2, are held as a unit in the die stock or other hand or machine appliance utilized for holding and turning the die for a threading operation. Other means than the ring 6 and screw 7 55 may be employed for holding the die sections 1 and 2 locked tightly together.

The die may be opened out as shown in Fig. 4, when it is removed from the ring 6, and this enables it to be re-sharpened at any time by using a high-speed emery wheel as illustrated in Fig. 8 which, however, shows the re-sharpening of the modified form of die illustrated in Figs. 5 to 7 inclusive.

Instead of the particular hinge connection shown in Figs. 1 to 4 inclusive, the sections 1 and 2 may be connected by a link 8 which is hinged to the sections at 9, as illustrated in Figs. 5 to 8 inclusive. The die of Figs. 5 to 8 will be held in a chuck or 70 ring as shown in Fig. 2.

When the die becomes worn, it is removed from the ring or chuck 6, opened out as shown in Fig. 8 and re-sharpened by the emery wheel 10, and then replaced in the 75 ring 6 for further use.

What I claim, is:

A threading die comprising threading sections which are hinged together and whose free ends abut, a ring in which, when said hinged abutting sections are placed, they are held in closed and immovable position, and means for locking the sections in immovable and closed arrangement in said ring so that they are unitary with the ring, enabling the sections and the ring to be applied to, or removed from, a die stock as a unit.

In testimony whereof I affix my signature.

GEORGE ELMER EASTHAM.
